ELECTRON DISCHARGE DEVICES

Edward C. Dench, Needham, Mass., assignor to Raytheon Manufacturing Company, Newton, Mass., a corporation of Delaware

Application July 28, 1951, Serial No. 239,114

5 Claims. (Cl. 315—39.3)

This invention relates to electron discharge devices, and more particularly to electron discharge devices of the magnetron type.

Magnetron oscillators have been developed to a high degree of efficiency and reliability as sources of high frequency of microwave energy. In the microwave region, magnetron oscillators are of outstanding importance, since they are more efficient than any of the other known types of high frequency oscillation generators. The field of application of magnetron oscillators has, however, been restricted, due to the difficulty heretofore encountered in linearly modulating the amplitude output of the magnetron. While it is well known that magnetron oscillators may be pulse modulated by pulsing the plate voltage applied to the magnetron, such modulation is restricted to applications where it is desired that the output be either zero or some maximum value as, for example, in pulse echo radar applications. Attempts to produce modulation of the output of the magnetron oscillator to obtain values between zero and maximum output by variation of the anode voltage have been unsatisfactory, since the magnetron oscillator output does not vary linearly with variation of the anode voltage.

Moreover, at values of the anode voltage where less than maximum power output is produced, the magnetron oscillator is likely to operate in an entirely different mode, producing a different output power and a different output frequency at a substantially reduced efficiency.

This invention discloses a structure, whereby the output amplitude of a magnetron oscillator may be varied in a substantially linear manner with respect to a modulation input signal.

Briefly, this invention comprises a grid structure insulated from both the anode and the cathode of a magnetron and positioned outside the main electron stream but in close proximity thereto and adjacent the portions of the anode members which are closest to the cathode. While the grid structure may be of any desired type and shape, it is desirable that the surface thereof be contoured to act upon the main electron stream along a considerable portion thereof.

By varying the potential applied to the grid structure with respect to the anode structure, the amplitude output of the oscillations generated by the device may be varied. The grid structure draws little or no current, and, therefore, the modulating power required to produce a high degree of modulation of the output is relatively small.

In addition, the grid structure may be designed to have a relatively low capacitance with respect to the anode and cathode, and, therefore, the upper limit of the range of modulation frequencies which may be effectively applied to the grid structure is relatively high, being, for example, on the order of several megacycles.

This invention further discloses a plurality of specific embodiments which have been found to be particularly useful. In a first embodiment, the magnetron oscillator comprises a plurality of anode members insulatedly sup-

2

ported in spaced relation with respect to a cathode. A lumped constant transmission line connects adjacent of the anode members together. Such a device has been found to be useful for generating oscillations at frequencies on the order of a few hundred megacycles. The grid structure comprises an auxiliary electrode made up of a pair of adjacent anode members which is connected together and insulated with respect to the remainder of the anode members. The main anode structure comprising all anode members other than the aforesaid pair of anode members constitutes a nonreentrant slow wave energy transmission structure. The grid structure or control electrode is positioned entirely within the gap formed between the ends of this nonreentrant structure.

This invention further discloses another embodiment of a magnetron oscillator adapted to operate in the microwave region. This device comprises a cavity magnetron from which three of the anode members have been removed so as to form a nonreentrant slow wave energy transmission structure. A grid structure has been substituted for the removed anode members, said structure having a curved inner surface spaced from the cathode by a distance substantially equal to the distance between the cathode and the anode member tips. This grid structure is positioned entirely within the gap formed between the ends of the nonreentrant structure.

Other and further objects and advantages of this invention will become apparent as the description thereof progresses, reference being had to the accompanying drawings, wherein:

Fig. 1 illustrates a partially broken away, transverse, cross-sectional view of a first embodiment of this invention;

Fig. 2 illustrates a longitudinal, cross-sectional view of the device illustrated in Fig. 1, taken along line 2—2 of Fig. 1;

Fig. 3 illustrates a partially broken away, transverse, cross-sectional view of a further embodiment of this invention; and

Fig. 4 illustrates diagrammatically a modulation system in which the devices illustrated in Figs. 1, 2 or 3 may be used.

Referring now to Figs. 1 and 2, there is shown a magnetron-anode structure comprising an anode cylinder 10 whose ends are closed by upper and lower end plates 11 and 12, respectively. Lower end plate 12 has an aperture 13 therein into which is sealed a metallic cylinder 14. The lower end of cylinder 14 is sealed by a glass bead 15. Bead 15 was sealed to cylinder 14 following evacuation and processing of the device. Upper end plate 11 contains an aperture 16 therein through which extends a cathode support cylinder 17, the inner end of which is connected to a cathode structure 18. Cathode structure 18 comprises a substantially continuous cathode cylinder 19 coated with electron-emissive material. The ends of cylinder 19 are closed by end shields 20 comprising disks of slightly larger diameter than the cylinder 19. Disks 20, cylinder 19 and cylinder 10 are all positioned coaxially, the portions of disks 20 which overhang cylinder 19 acting to prevent substantial movement of electrons emitted from the coating on cylinder 19 in a direction parallel to the axis thereof. Support cylinder 17 is somewhat smaller in diameter than the aperture 16 in end plate 11, and, accordingly, is spaced from end plate 11 at it passes therethrough.

A support cylinder 21 of insulating material, such as glass, surrounds support cylinder 17 coaxial therewith, one end of cylinder 21 being sealed into a recess in end plate 11 surrounding aperture 16. The other end of cylinder 21 which is outside the evacuated space defined by cylinder 10 and end plates 11 and 12 is sealed to a

metal cup 22 which, in turn, is attached to support cylinder 17. The end of cylinder 17 which extends out beyond cup 22 is attached to a glass sealing cylinder 23 which, in turn, is sealed to a metallic cup 24. Cup 24, in turn, is attached to an electrode structure 25 connected to a rod 26 which extends through support cylinder 17 spaced therefrom into the interior of the cathode structure 18 where it is connected to one end of a heater coil, not shown. The other end of the heater coil is connected to cathode cylinder 19 such that, by application of a heater voltage supply between electrode 25 and cup 22 by means of a heater voltage supply 27, a heater current will flow in the heater coil, thereby heating cathode cylinder 19 and causing the coating thereon to emit electrons.

Surrounding cathode structure 18 and spaced therefrom is a plurality of anode members 28. Anode members 28 are rods of conductive material whose axes are positioned parallel to the axis of anode cylinder 10 and cathode structure 18. Rods 28 extend out through apertures in upper end plate 11 and are insulated therefrom by means of ceramic beads 29 which seal rods 28 into the apertures in plate 11 and rigidly support them with respect thereto. Inductors 30 and capacitors 31 are connected to the external ends of rods 28 to form a lumped constant transmission line having a low frequency pass characteristic.

This is accomplished in the following manner. Adjacent anode members are connected together through inductors, and are connected to a common ground plane for high frequencies, namely, upper end plate 11, through capacitors. The inductors 30 are mounted on support rings 32 and 33 which are supported with respect to end plate 11 by means of rods 34. A magnetic field is maintained in the space between cathode 18 and anode members 28 by means of a coil 35 surrounding anode cylinder 10 and through which may be passed a magnetizing current. One pair of adjacent anode members, designated by 36, is connected directly together and is insulated from the remainder of the anode members, since none of the inductors 30 and capacitors 31 is connected to the members 36. The main anode structure comprising all anode members other than members 36 constitutes a nonreentrant slow wave energy transmission structure. Members 36 form an auxiliary electrode which is connected to one terminal of a modulation source 37, the other terminal of which is connected to the anode cylinder 10. An anode voltage supply 38 is provided, one side of which is connected to cup 22, and the other side of which is connected through a high impedance 39 to one of the anode members 28. Impedance 39 prevents loading of the transmission line by the power supply 38 at the operating frequency of the device.

The specific details of the inductors, capacitors and anode members are more clearly set forth in copending application, Serial No. 81,804, filed March 16, 1949, by William C. Brown and Edward C. Dench, entitled Magnetron Amplifier, now Patent No. 2,673,306, issued March 23, 1954, to William C. Brown. In addition, the aforesaid copending application describes the method whereby the anode members 28, inductors 30 and capacitors 31 form a network which will interact with electrons from the cathode in the presence of crossed electrostatic and electromagnetic fields to produce oscillations whose frequency is determined by the cutoff frequency of the anode structure. This frequency is commonly called π mode of operation of the device. An output for the device is provided by merely connecting a wire to one of the anode members, as at 40.

Referring now to Fig. 3, there is shown a further embodiment of this invention wherein the anode structure is of the cavity resonator type adapted to operate at microwave frequencies. The anode structure comprises

an anode cylinder 41. Extending radially inwardly from the inner surface of cylinder 41 is a plurality of anode members 42 comprising substantially planar conductors. Adjacent pairs of anode members 42, together with the space therebetween, define cavity resonators. Alternate anode members 42 are connected together at points adjacent their inner ends on their upper and lower sides by conductive strapping 43 in order to eliminate spurious modes of oscillation of the device.

10 Positioned inside the space defined by the inner ends of the anode members 42 is a cathode structure 44 comprising a cathode cylinder coated with electron-emissive material. Cathode 44 is substantially similar to cathode 18 described in connection with Figs. 1 and 2. Cathode 15 44 is supported with respect to an end plate 45 closing one end of cylinder 41 in substantially the same manner that cathode 18 is supported with respect to end plate 11 in Figs. 1 and 2.

An output coupling device 46 is provided comprising 20 a conductive rod 47, one end of which is connected to the conductive strapping 43, and the other end of which extends out through an aperture 48 in cylinder 41. A conductive cylinder 49 is threadedly sealed into aperture 48 and extends outwardly from cylinder 41 surrounding 25 conductive rod 47 but spaced therefrom. A glass seal 50 is provided between conductive rod 47 and outer conductor 49 to maintain a vacuum within the device.

At a point in the anode structure substantially opposite to the output coupling device 46, three of the anode 30 members 42, together with the conductive strapping 43 associated therewith, have been eliminated. An auxiliary electrode or grid 51 has been substituted for the three anode members, said auxiliary electrode or grid comprising a conductive member 52 positioned adjacent the inner ends of the anode members 42. The anode structure comprises anode cylinder 41, anode members 42, and conductive strapping 43. This anode structure constitutes a nonre-entrant slow-wave energy transmission structure. The inner surface of member 52 which faces the cathode 44 is curved to conform to the contour of the average electron path which runs circularly about the cathode in the space between the anode members 42 and the cathode. Member 52 is supported by means of 35 a rod 53 which extends outwardly through anode cylinder 41 and is sealed by means of a glass seal 54 to an outer conductive cylinder 55 surrounding rod 53 and sealed to cylinder 41. The grid 51 is positioned entirely within the gap formed between the ends of the nonre- 40 entrant slow wave energy transmission structure. It is to be clearly understood that, while the device shown in Figs. 1 and 2 is of the unstrapped anode structure type while the device shown in Fig. 3 is of the strapped anode structure type, either a strapped anode or unstrapped anode design could be used for both the species of Figs. 1 and 2 and the species of Fig. 3.

Referring now to Fig. 4, there is shown diagrammatically a modulation system in which the devices of Figs. 1 and 2 or 3 may be used. There is shown a magnetron 60 device 56 comprising an anode structure 57, cathode structure 58 and auxiliary electrode or grid structure 59 which may be of the type illustrated in Figs. 1 and 2 or of the type illustrated in Fig. 3.

An anode voltage supply 60 is connected between the 65 anode structure 57 and the cathode structure 58. The auxiliary electrode or grid 59 is connected to one end of the secondary winding 61 of a signal input transformer 62. The other end of secondary winding 61 is connected to the variable tap 63 of a potentiometer 64 which is connected across a battery 65. Battery 65 is connected by a tap 66 substantially at its mid point to cathode 58. The primary winding 67 of transformer 62 is connected to a modulation source which may have a frequency extending from the lower audio range up to a frequency of several megacycles.

By adjusting the tap 63 of potentiometer 64, the bias applied to auxiliary electrode or grid 59 may be made either positive or negative with respect to the cathode 58, dependent upon the average power output which is desired from the magnetron oscillator 56. With modulation voltages applied between the cathode 58 and the auxiliary electrode or grid 59 whose peak amplitudes are on the same order of magnitude as the amplitude of the anode supply voltage, substantially one hundred percent modulation may be achieved by means of this device. If desired, the bias supply may be eliminated and the modulation source connected directly between the anode and the auxiliary electrode or grid, as illustrated in Fig. 1, or between the auxiliary electrode or grid and the cathode.

This completes the description of the particular embodiments of the invention illustrated herein. However, many modifications thereof will be apparent to persons skilled in the art without departing from the spirit and scope of this invention. For example, other forms of anode structures and auxiliary electrode or grid structures may be used, and the positioning of the auxiliary electrode or grid may be varied somewhat from that disclosed herein, depending upon the results desired. Accordingly, it is desired that this invention be not limited by the particular details described herein, except as defined by the appended claims.

What is claimed is:

1. An electron discharge device comprising a non-reentrant slow wave transmission network the ends of which are separated by a gap, a cathode arranged substantially parallel to said network, means for directing a beam of electrons from said cathode adjacent said network in energy-exchanging relation with radio-frequency fields existing along said network, a control electrode positioned entirely within said gap and adjacent the portions of said network which are in proximity with said cathode, and signal input means coupled to said control electrode for modulating the output of said device.

2. An electron discharge device comprising a non-reentrant slow wave transmission network the ends of which are separated by a gap, a source of electrons spaced along a region adjacent a substantial portion of said network, means for directing a beam of electrons from said source adjacent said network in energy-exchanging relation with radio-frequency fields existing along said network, said means for directing including means for producing a magnetic field in the space between said electron source and said network, a grid structure disposed entirely within said gap and adjacent the portions of said network which are in proximity with said source of electrons, and means for supplying a modulation input signal to said grid structure for modulating the output of said device.

3. An electron discharge device comprising a non-reentrant slow wave transmission network the ends of which are separated by a gap, a source of electrons spaced along a region adjacent a substantial portion of said network, means for directing a beam of electrons from said source adjacent said network in energy-exchanging relation with radio-frequency fields existing along said network, said means for directing including means for producing a magnetic field in the space between said electron source and said network, a control electrode positioned entirely within said gap outside the path occupied by the electron beam and disposed adjacent to portions of said network which are in proximity with said source of electrons, and signal input means coupled to said control electrode for modulating the output of said device.

4. An electron discharge device comprising a non-reentrant slow wave transmission network the ends of which are separated by a gap, a source of electrons spaced along a region adjacent a substantial portion of said network, means for directing a beam of electrons from said source adjacent said network in energy-exchanging relation with radio-frequency fields existing along said network, said means for directing including means for producing an electrostatic field between said electron source and said network and means for producing a magnetic field in the region between said source and said network substantially perpendicular to said electrostatic field, a grid structure disposed entirely in said gap and adjacent to portions of said network which are in proximity with said electron source, and means for applying a modulation input signal to said grid structure for modulating the output of said device.

5. An electron discharge device as recited in claim 4 wherein said network comprises a plurality of members alternate ones of which are interconnected by electrically conductive strapping.
